UNITED STATES PATENT OFFICE

THOMAS WATKINS AND LORIN D. BAUM, OF BERKELEY, CALIFORNIA

WINDING DEVICE

Application filed November 11, 1929. Serial No. 406,326.

This invention is a winding device to be used for measuring fabric or cloth in bolt remnants for invoicing and has for its main object, the provision of an inexpensive device 5 in which a remnant of a bolt of cloth may be readily mounted by means of the core board, the cloth being passed from the bolt into cooperation with a measuring device of known manufacture, and rewound on another core 10 board by means of a hand operated crank handle.

Another object of the invention is to provide a winding device which is simple in construction and operation and inexpensive to 15 manufacture.

A further object of the invention is to provide a winding device which will not be inclined to stretch the material during the rewinding of the bolt.

20 Other objects and advantages of the invention will become apparent as the following description is read on the drawing forming a part of this specification and in which similar reference characters are used to designate 25 similar parts throughout the several views and in which:

Fig. 1 is a side elevation of the invention.

Fig. 2 is a plan view of the invention showing core boards in place.

30 Fig. 3 an end elevation of Fig. 2.

Fig. 4 is a broken detail view of the core board retaining spring finger.

Fig. 5 is a sectional view taken on line 5—5 35 of Fig. 4.

The invention consists of two similar, oppositely disposed side frames, each side frame consisting of a base member 10, having fixedly mounted at each end, terminal standards 13, the standards being secured to the base members with clip angles 4 or other suitable 40 means.

Intermediate the terminal standards 13 and spaced apart are two guide supporting standards 14 which are secured to the base members 10 by means of clip angles 15. Suitable crossbracing 16 is provided between the end standards and the adjacent intermediate standard and a strut 17 between the intermediate standards completes the bracing of the structure.

A bearing is provided adjacent the top of each terminal standard for shafts 19 by securing a clip angle 18 to the upper portion of the standards 13 and forming a suitable hole through the opposed legs of the 55 standard and clip angle, as indicated.

The core board heads consists of a head bar 21, which is intermediately secured on the shaft 19, one of the shafts 19 having an extension which is formed into a crank arm 27 on 60 which a handle 28 is pivotally secured.

The core board retaining fingers 22 consist of a bar of resilient material bent to U form adapted to resiliently secure the board 23 between the fingers as shown in Fig. 5, the 65 fingers being secured by means of a rivet 20 passing through the intermediate connecting portion of the fingers and the bar 21.

Fixedly secured, and vertically spaced adjacent the upper end of intermediate 70 standards 14 as indicated at 24 are sections of pipe 25, inside of which is disposed a round bar 26 and which is slidably fitted in one of the pipes of each pair, thereby permitting transverse adjustment of the side frames. 75

The two base members 10 are adjustably connected by means of the transverse cooperating bars 11 and 12, the bolts 29 being threadedly fixed in the bar 11 and passing through slots in bar 12 as is customarily done. 80

The space between the telescopic guides 25—26 is in a plane with the core boards 23 when mounted in the spring fingers, whereby they act only as an intermediate support for the cloth as it passes from one 85 core board to the other.

Any suitable measuring device may be mounted on one of the standards 14, so as to cooperate with the cloth as it passes from one core to the other.

The device is used by first spreading the frames so as to permit mounting of the bolt by passing the core board between the spring fingers under the cloth, then adjusting the side frames toward each other until the core boards engage the connecting member of the spring fingers.

The end of the cloth is then passed between each pair of guides 25 and secured to the core board at the crank operated end of the device 100

by inserting the end of the cloth between the board and the spring fingers.

The cloth is then wound from one core board to the other, the measuring device co-
6 operating with the cloth as it passed from one core board to the other.

Having described an operable method of constructing and using the invention it will be noted that variations in construction and
10 arrangement of parts which are consistent with the appended claims may be resorted to without detracting from the spirit or scope of the invention or sacrificing any of the advantages thereof.

15 We claim:

1. A winding device consisting of a pair of base members transversely adjustable relative to each other, telescopic adjusting members connecting said base members, a standard at
20 each end of each base member, a bolt core retaining device rotatably mounted on each of said standards and intermediate pairs of standards, each pair connected by two spaced apart telescopic guides.

25 2. A winding device consisting of a pair of base members transversely adjustable relative to each other, telescopic adjusting members connecting said base members, a standard secured at each end of each base member,
30 a bolt core holder provided with friction gripping fingers rotatably mounted on each of said standards and two pair of spaced intermediate standards each pair being connected transversely by two spaced apart parallel, telescopic guides.

3. A winding device comprising a pair of base members transversely adjustable, standards at each end of each base member, a bolt core retaining device rotatably mounted ad-
40 jacent the top of each end standard, two intermediate standards for each base member forming two pair of standards and two telescopic guides connecting each pair of stand-
ards and spaced apart, said guides being
45 adapted to receive a strip of material there-
between passing from a core board mounted in the core retaining devices at one end to a core board mounted in the core retaining devices at the other end, and a crank for oper-
50 ating one of said core retaining devices.

In testimony whereof we affix our sig-
natures.

THOMAS WATKINS.
LORIN D. BAUM.
